CLAIM

The ornamental design for the shelter for electrical cord connections or the like, as shown and described.

DESCRIPTION

FIG. 1 is a bottom perspective view of a shelter for electrical cord connections or the like showing the claimed design; FIG. 2 is a top perspective view thereof; FIG. 3 is a front view thereof; the rear, left side, and right side views being identical to the front view; FIG. 4 is a top view thereof; FIG. 5 is a bottom view thereof; and, FIG. 6 is a top perspective view thereof in an environment in which it may be used.

The dashed broken lines in the figures show portions of the shelter for electrical cord connections or the like or environmental subject matter that form no part of the claimed design. The dot-dash broken lines in the figures show boundaries that form no part of the claimed design. The shade lines in the figures show contour and not surface ornamentation.
